Samuel Springer
Inventor

United States Patent Office.

SAMUEL SPRINGER, OF CHICAGO, ILLINOIS.

Letters Patent No. 101,327, dated March 29, 1870.

IMPROVED BED-FRAME.

The Schedule referred to in these Letters Patent and making part of the same

To all whom it may concern:

Be it known that I, SAMUEL SPRINGER, of the city of Chicago, in the county of Cook, and State of Illinois have invented certain new and useful Improvements in Bed-Frames; and I do hereby declare that the following is a full, clear, and exact description thereof, reference being had to the accompanying drawings making a part of this specification, in which—

Figure 1 is a perspective view of the frame;

Figure 2 a transverse section of two of the sections;

Figure 3 a partial longitudinal section, and

Figure 4 a perspective view of one section.

The object of my invention is to provide a bed so made in longitudinal sections that it can be readily separated into two, three, or more beds when desired for use, and when not in use so that it can be put together again and only occupy the space of an ordinary bedstead, and so that the upper one may be used without separating its sections; and

Its nature consists in so constructing a bed-frame and connecting its parts that it may be used as a single bed, or separated into two, three, or more beds, as may be desired.

To enable others skilled in the art to make and use my improvements, I will proceed to describe the same.

The head and foot-boards A are made alike, and are made of the ordinary length, and about ten inches wide.

The side boards B are also made of the usual length, and from six to eight inches wide, they being left somewhat narrower than the head and foot-boards for the purpose of ventilation.

The posts D are of any suitable size, and at the upper ends are cut away, as shown at a, and at the lower ends have a projection, b, which fits into a, when the sections 1, 2, and 3 are placed together and operate as legs for keeping the frame above the floor when the sections are separated, as shown at fig. 3.

I use the ordinary fastenings for securing the side boards or rails to the post. The fastenings may be made to connect directly with the head and foot-boards, and strong dowels or smaller posts, fastened into the corners and projecting below the frame, may be used in place of the posts shown.

Slats, C, or other suitable supports for the bedding, are placed in each section of the frame, and secured thereto in any of the well-known modes.

I usually make this frame plain, and of cheap material, as its use is mainly confined to such places as have a scarcity of room, or temporary accommodations only are required, such as camp-meetings, barracks, and hotels in times of fairs or conventions, and small houses occupied by large families. They are not much more expensive than bunks and are much superior in use, as when put away they occupy less space, and when in use are spread out so as to be as comfortable as ordinary beds, and, as the beds are "made" before being placed together, the clothing is much more easily handled and evenly made up.

In the frame shown, the lower section i has no provision at the bottom for interlacing with the other sections, and it is not necessary; but usually it will be found best to make these all alike, so that no care will be required in putting them up.

Having thus fully described my improved bed-frame, What I claim as new and desire to secure by Letters Patent, is—

A bed-frame made in longitudinal sections, and so connected that the said frame may be used as a single bedstead or be separated into two or more, substantially as and for the purposes specified.

SAMUEL SPRINGER.
